UNITED STATES PATENT OFFICE.

RALPH L. LOVELL AND FREDERICK P. PALEN, OF NEWPORT NEWS,
VIRGINIA.

AUTOMATIC BRAKE FOR HOISTING-MACHINES.

SPECIFICATION forming part of Letters Patent No. 738,556, dated September 8, 1903.

Application filed May 12, 1903. Serial No. 156,850. (No model.)

To all whom it may concern:

Be it known that we, RALPH L. LOVELL and FREDERICK P. PALEN, citizens of the United States, both residing at Newport News, in the county of Warwick, State of Virginia, have invented a new and useful Improvement in Automatic Brakes for Use on Hoisting-Machines, of which the following is a specification.

10 Our invention consists of an improved automatic brake for use in a hoisting-machine, which acts to hold the suspended load at any desired point and to resist its descent.

15 It further consists of novel details of construction hereinafter set forth.

Figure 1 represents a top plan view of our device. Fig. 2 represents the same device partly in vertical section. Fig. 3 represents an elevation of a friction-cone and ratchet 20 employed. Fig. 4 represents, partly in elevation and partly in vertical section, a modified form of the essential features of our device.

25 Similar numerals of reference indicate corresponding parts in the figures.

Referring to Figs. 1, 2, and 3 of the drawings, 1 designates the base, provided with internal gear-teeth 2. 3 is a step-plate in which is stepped a mast 4. To this mast may of 30 course be attached the usual boom or gaff. (Not shown.) Mounted on the step-plate 3 is a motor 5, connected by suitable gear 6 and worm 7 to connected spur wheels or pinions 8, the teeth of the latter meshing with the 35 teeth 2 of the base 1. Any other convenient means for swinging the load by means of the rotation of the mast and step-plate may be used. The step-plate 3 also carries a motor 9, connected by gears 10 to a worm-shaft 11, 40 to which is suitably secured a worm 12. I prefer, for reasons hereinafter apparent, to forge or mount on the shaft 11 a collar 13, against which the worm 12 thrusts. Meshing with the worm 12 is a worm-wheel 14, which 45 serves to rotate a hoisting-drum 15, suitably supported on the step-plate 3. From the drum 15 leads a rope 16 to the supported load. (Not shown.) Near one end of the shaft 11 is secured a ratchet-wheel 17, in the teeth 50 of which engages a plurality of pawls 18, connected to a friction-cone 19. The cone 19

bears against the inner surface of a stationary cone-case 20.

Figs. 2 and 3 of the drawings clearly show that a rotation of the shaft 11 in the direction to wind the rope 16 on the drum 15, and thus to hoist the load, permits the pawls 18 to click on the ratchet 17, leaving the cone 19 stationary. The thrust of the shaft is in this case taken by the washer 21 in the cone 60 19. When the motion is reversed to lower the load, the pawls 18 lock with the ratchet 17 and cause the cone 19 to turn in the case 20. The angle of the contact-surfaces may be so adjusted as to produce any desired 65 amount of friction. It is evident that this friction varies directly with the load weight, any increase in which causes a proportionately greater thrust of the shaft 11 toward the cone-case 20. It is of course desirable 70 that the friction of the cone in its case shall exceed the gravitational force of the load, whereby the load is safely held at any desired point. By making the friction equal to twice the load the duty of the motor is substantially the same when running in either 75 direction.

In Fig. 4 of the drawings we have shown the friction device directly connected to the shaft of the drum, the enlarged shaft 22 of 80 which is cut off at an angle corresponding to that of a subsidiary shaft 23, running in the same bearing 24 to which the ratchet 17 is attached. It is clear that when the pawls 18 are locked with the ratchet 17, as in lowering the load, the end of the shaft 22 will ride as a cam on the end of the shaft 23, thereby producing the desired thrust of the cone 19 into the case 20.

It will be evident that various changes may 90 be made in the art which may come within the scope of our invention, and we do not therefore desire to be limited to the exact construction herein shown and described.

Having thus described our invention, what 95 we claim as new, and desire to secure by Letters Patent, is—

1. An automatic brake for a hoisting-machine consisting of a friction-cone and a case, a shaft on which one of said brake portions 100 is loosely mounted, a ratchet mounted on said shaft and engaged with said brake por-

tion when the drum of said machine is rotated in one direction only, and means connected with said drum for producing on said shaft a longitudinal thrust, variable with the weight 5 of the suspended load.

2. In a hoisting-machine, a power-actuated shaft, a drum driven by said shaft, a friction-cone loosely mounted on said shaft, a case in which said cone rotates and means for locking 10 said cone to said shaft, the parts being so arranged that the rotation of said drum in a direction to lower a suspended load, acts to lock said cone to said shaft, and to thrust said shaft toward said case.

15 3. In a hoisting-machine, a power-actuated

shaft, a worm secured to said shaft, a hoisting-drum driven by said worm, a friction-cone loosely mounted on said shaft, a case in which said cone rotates, and means for locking 20 said cone to said shaft, the parts being so arranged that the rotation of said drum in the direction to lower a suspended load, acts to lock said cone to said shaft and to thrust said shaft toward said case.

RALPH L. LOVELL.
FREDERICK P. PALEN.
